PAGE 3

Fig. 5.

Fig. 4.

Figure 1 is a perspective view of a combined riding tractor and power mower embodying our new design, viewing the same from the left front,

Figure 2 is a perspective viewing the same from the right rear,

Figure 3 is a perspective viewing the same from the right side,

Figure 4 is a front perspective view, and

Figure 5 is a rear perspective view.

The dominant features of our design reside in those portions thereof illustrated in full lines.

We claim:

The ornamental design for a combined riding tractor and power mower, as shown and described.
